UNITED STATES PATENT OFFICE.

JESSE MERCER, OF BENTON, AND ED MERCER, OF WEST FRANKFORT, ILLINOIS.

SIGN.

Application filed May 29, 1925. Serial No. 33,739.

To all whom it may concern:

Be it known that we, JESSE MERCER and ED MERCER, citizens of the United States, residing at Benton and West Frankfort, respectively, in the county of Franklin and State of Illinois, have invented new and useful Improvements in Signs, of which the following is a specification.

This invention relates broadly to signs and has for its primary object the provision of a sign which may also be utilized as a signal especially adapted for location at dangerous points along a roadway, such as at curves, road intersections, railroad crossings or boulevard stops.

Another object of the invention is the provision of a signal sign which is adapted to be positioned to receive the rays of light from the lamps of approaching vehicles and to reflect said rays in a manner to attract the attention of the driver and other persons along the roadway so as to warn the driver that he is approaching a point of possible danger and to warn others of the approach of the vehicle.

A further object of the invention is the provision of a sign signal which in addition to the above and other advantages embodies novel details of construction, whereby certain elements are interchangeable which permits of the sign being arranged to suit different road conditions and different purposes.

With the above and other objects in view, the invention further includes the following novel features and details of construction, to be hereinafter more fully described, illustrated in the accompanying drawings and pointed out in the appended claim.

40 In the drawings:—

Figure 1 is a front elevation of a sign signal constructed in accordance with the invention.

Figure 2 is a vertical sectional view of the same.

Figure 3 is a rear elevation.

Figure 4 is an enlarged fragmentary sectional view taken through the lens carrying panel.

50 Figure 5 is an enlarged fragmentary section taken on the line 5—5 of Figure 1.

Referring to the drawings in detail wherein like characters of reference denote corresponding parts, the reference character 10 indicates a support which may be of any suitable character, but which preferably con-

sists of a pipe or standard having its upper portion flattened as illustrated in Figures 2 and 3 of the drawings. This standard supports a frame which includes parallel side bars 11 and 12 and end bars 13, all of which are preferably longitudinally grooved as illustrated at 14 in Figures 4 and 5 of the drawings. One of the side bars, for example, the side bar 12 is secured to the end bars by pins 15. These pins may be removably held in place by any suitable means so that one of the pins may be removed while the other pin may act as a pivot, whereby the bar 12 may be swung outward. The frame further includes an intermediate bar 16 whose opposite edges are longitudinally grooved as indicated at 17 in Figure 2 of the drawings. If desired, the sign may include a supplemental frame 18 which is constructed in substantially the same manner as the frame just described and this supplemental frame may be secured to the main frame by straps or similar fastening devices 19. A hook-shaped element 20 extends from the standard and provides a seat for the lower bar 13 of the main frame, while the supplemental frame is held in place by a bolt or similar fastening device 21. A cross bar 22 preferably extends transversely of the standard 10 and the opposite ends of this cross bar are shaped to provide hooks 23 which engage around the side bars 11 and 12 of the frame so that the said frame will be securely held in place.

Slidable within the grooves of the main frame between the upper end bar 13 and the intermediate bar 16 is an aluminum or other panel 24 which serves as a backing for a tin or other sheet metal plate 25, the latter having the words "Safety first", "Look" and "Side road" thereon, or other desired warning or indicia. The words are preferably of a luminous character so as to be readily seen both day and night. The tin or sheet metal panel 25 is preferably covered by a glass panel 26 so as to protect the lettering thereon from the elements.

Located within the grooves of the frame between the lower end of the bar 13 and the intermediate bar 16 are a preferably aluminum panel 27 and a second aluminum panel 28, the said panels being spaced apart while the panel 28 is provided with a plurality of openings 29. The space between the panels 28 and 29 is filled with a suitable plastic material such as putty, indicated at 30 and

set within this material and extending through the openings 29 are a number of light reflecting elements 31. These light reflecting elements may be of any suitable 5 shape or design, the ones shown consisting of circular concavo-convex lenses having a multiplicity of faces on their convex sides. These elements provide light reflecting members which serve to readily attract attention when located in the path of the rays 10 of light from an automobile or other relatively powerful light.

The supplemental frame 18 may be provided with a preferably aluminum panel 32 15 which forms a backing for a mirror 33 and a glass panel 34, the latter preferably having imprinted thereon in red or other attractive color the word "Danger".

It will be apparent from the foregoing 20 description and accompanying drawings that the sign signal may be placed at a convenient point and at desired locations along a roadway for the purpose of warning the public of possible danger points, the character 25 of the invention serving to provide a signal or warning both day and night.

Further the construction is such that the panels may be removed and others substituted and the sign may consist of any number of panels.

30

The invention is susceptible of various changes in its form, proportions and minor details of construction and the right is herein reserved to make such changes as properly fall within the scope of the appended 35 35 claim.

Having described the invention what is claimed is:—

A sign comprising a support, a frame mounted thereon, separate panels mounted 40 in said frame, one of said panels including spaced plates, one of which is provided with a plurality of openings, light reflecting elements extending through said openings and means located between the plates and engaging the light reflecting elements to hold the latter in position.

In testimony whereof we affix our signatures.

JESSE MERCER.
ED MERCER.
